UNITED STATES PATENT OFFICE.

GUSTAV ANKELEN, OF ST. LOUIS, MISSOURI.

INDEX-TAB FOR BOOKS, &c.

SPECIFICATION forming part of Letters Patent No. 274,248, dated March 20, 1883.
Application filed December 1, 1882. (No model.)

To all whom it may concern:

Be it known that I, GUSTAV ANKELEN, a subject of the Emperor of Germany, having declared his intention of becoming a citizen of the United States, residing at St. Louis, and State of Missouri, have invented a new and useful Index-Tab for Books, &c., of which the following is a specification.

This invention relates to improved manner and means to provide an alphabetical index or "leather tabs" for the fore edge of books, folded sheets, and similar purposes.

The essential objects of my invention are to achieve greater strength, durability, and neatness, both on part the leather tab or index proper, and its attachment to the edge of the paper, sheet, book, &c., also to render the said parts more impervious and capable of resisting the effects of handling, and otherwise to improve the fore edge of books, &c., to which my improvements are applied. I achieve the said objects by the mechanism illustrated in the accompanying drawings, in which—

Figure 1 represents in perspective a book having my improved index-tab applied thereto. Fig. 2 is an enlarged perspective view of the index-tab as it appears ready to be applied. Fig. 3 is a transverse section of Fig. 2. Fig. 4 is a transverse section of the index tab as it appears when applied or attached to the fore edge of a leaf, sheet, or book. Fig. 5 represents in detail perspective views the respective patterns or cuts of all the parts that compose my improved index-tab.

Similar letters refer to similar parts throughout the several views.

A represents the well-known leather tab upon which the alphabetical letters are impressed, printed, &c. As usual, the said leather tab consists of two folds; and each of these I shape to present the hook-shaped projecting edges or flaps at $a a'$, as shown in Figs. 2, 3, 4, 5.

B represents the pasteboard, cloth, or filling that is placed inside the folds of the leather tab A, in order to give same thickness, strength, and body.

C represents the bottom layer or fold, consisting preferably of a rectangular piece of linen cloth cut and folded, as shown—that is to say, this piece of linen is doubled together

to present the folds marked $c c'$ and edge at c^2 , as shown in Figs. 2, 3, 4, 5. Upon the inner faces of the folds $c c'$ glue or adhesive coating is applied in order to attach the linen fold C to the fore edge. Hence this fore edge, X, 55 of the book, &c., comes between the folds $c c'$, and up against or in contact with the edge c^2 of the linen fold C, as indicated in Figs. 3, 4. The fore edge, X, is thus strengthened by the addition of this bottom linen fold, C, and the 60 latter serves as the means or surfaces against which the leather tab A is attached or made to adhere. For this purpose the leather tab A has its hook-shaped edge or faces $a a'$ only pasted, glued, or attached near to the edge c^2 65 of the linen fold C, as shown in dotted lines in Fig. 2. In practice, I place the "filling" B first between the leather folds of the tab A, and then spread the hook-shaped folds $a a'$ to come over the edge of C, as indicated, and 70 press the parts together to cause the adhesion to take place, thus leaving only the index or leather tab to project beyond the fore edge in manner usual. The linen fold C, and attached thereto its leather tab A, I further join 75 firmly together by a third layer or outer fold of linen, (marked D.) This piece is made and folded in the shape shown in Fig. 5, so as to have the folds $d d'$ and edge at d^2 . Further, this edge d^2 is cut to have an opening or hole, 80 d^3 , of such size as to simply permit the linen fold D to be slipped over the leather tab, and bring said fold D in parallel lines to fit snugly over the bottom fold, C. It is the adhering or attachment of the outer linen fold, D, over 85 the hook-shaped edges $a a'$ of the leather tab that retains the latter more firmly in its place, and offers resistance to any act tending to tear the leather tab or index away. The two linen folds (bottom, C, and outer one, D,) come 90 in line, top, or over each other and by glue or other adhesive matter are made to adhere together, while the index-tab A, by its projecting edges $a a'$, at same time remain glued or fastened between the said two folds C and D. 95 The combination to the fore edge of a book or the like, of the two layers of linen folds C and D, and the leather tab or index having its edges $a a'$ between said layers forms a most strong, durable, and serviceable "index-tab," 100

and improved manner of firmly attaching same to the proper place indicated.

What I claim is—

As a new article of manufacture, the index-
5 tab consisting of the "tab" A proper, having
edges $a\ a'$, the bottom layer of linen, C, hav-
ing folds $c\ c'$, and edge c^2 , and the outer layer of
linen, D, having folds $d\ d'$, edge d^2 , and open-
ing d^3 , as and for the purposes set forth.

In testimony of said invention I have here-
unto set my hand.

GUSTAV ANKELEN.
